UNITED STATES PATENT OFFICE.

ROBERT A. GAWLER, OF CONCORD, NEW HAMPSHIRE.

IMPROVED CARPET-FASTENER.

Specification forming part of Letters Patent No. **59,002**, dated October 23, 1866.

To all whom it may concern:

Be it known that I, ROBERT A. GAWLER, of Concord, in Merrimack county, State of New Hampshire, have invented a Carpet-Fastener; and I do hereby declare the following description and accompanying drawings are sufficient to enable any person skilled in the art or science to which it most nearly appertains to make and use my said invention or improvements without further invention or experiment.

This invention consists in a hook shaped like a horseshoe, inserted in a shank so as to be capable of motion therein, for the purpose of fastening carpets to floors.

In the drawings, Figure 1 is a side elevation.

The same letters in different drawings refer to similar parts.

A represents the shank, consisting of any suitable and convenient metal. B represents the hook, horseshoe-shaped, as shown, with two points, b, considerably curved, as represented, so that they may get a firm hold upon the carpet. Said hook is inserted in an eye in the top of the shank in such manner as to be capable of motion in a vertical plane to any required extent. The wire of which the hook is composed is bent into the form represented after being inserted in the eye of the shank. C represents the carpet.

When in use the shanks of any desired number of these instruments are to be driven into the floor of the room to be carpeted, along the edges thereof, and the hooks are to be turned back against the wall, so that their points may

project upward. The edge of the carpet is then to be placed against the driven shanks, and the points of the hooks turned down into it and driven into the floor, if desired. The carpet is thus firmly secured at one side, and may be stretched to any required extent before being fastened at the other side in a similar manner. The hooks may be turned from the wall instead of toward it, at pleasure, and thus the carpet be fastened upon the hooks, their points projecting up through it.

When the carpet is to be taken up, it is only necessary to turn the hooks up out of it, or to take it up from the hooks, as the case may be—a process much more easily performed, and attended with much less injury to the fabric, than that of extracting tacks from it. It is also much easier to put down a carpet with these fasteners than with tacks, as the shanks are driven when the carpet is out of the way, and when it is put in position it is much less difficult to turn the points of the hooks down into it than to drive tacks.

Having thus described my invention, what I claim as new, and desire to secure by Letters Patent, is—

A carpet-fastener consisting of a shank, to be driven into the floor of a room, and a hook, horseshoe-shaped, as shown, working in said shank, in the manner described.

ROBERT A. GAWLER.
